UNITED STATES PATENT OFFICE

CARL E. L. LIPMAN, OF CHICAGO, ILLINOIS, ASSIGNOR TO LIPMAN PATENTS CORPORATION, OF CHICAGO, ILLINOIS, A CORPORATION OF DELAWARE

EVAPORATOR

Application filed February 27, 1931. Serial No. 518,745.

This invention relates to evaporators for use in refrigerating systems and to an evaporator that is particularly well suited for use in the so-called flooded systems.

5 It is the purpose of this invention to provide an evaporator that is efficient, economical to manufacture in particularly quantity production and readily assembled.

In accordance with this invention the evaporator is constructed of two unitary sections so constructed that they may be interleaved with each other and interconnected to provide one or more refrigerating chambers substantially surrounded by a refrigerating medium. In the preferred construction embodying the principles of this invention the evaporator comprises a pair of unitary sections, each of which is composed of a pair of spaced headers connected by spaced tubes, 20 the tubes being bent into irregular shape in such a manner that when the tubes of the two sections are interlaced or interleaved they will form one or more refrigerating chambers. In another substantially equivalent construction the tubes of each section may be returned to a single header, thus eliminating one header.

A better understanding may be had of this invention from the following description given in connection with the drawings in which:

Fig. 1 is a side elevation of an evaporator constructed in accordance with this invention,

35 Fig. 2 is a front elevation of the evaporator illustrated in Fig. 1,

Fig. 3 is a perspective view of the two unitary sections employed in making the evaporator shown in Figs. 1 and 2,

40 Fig. 4 is a front elevation of a modified form of this invention,

Fig. 5 is a front elevation of a still further modified form of this invention,

45 Fig. 6 is a perspective of a lining or sleeve, Fig. 7 is a perspective view of two still fur-

ther modified sections illustrated in spaced position prior to being placed together, and

Fig. 8 is an end elevation similar to Fig. 2 of an evaporator constructed of the modified sections shown in Fig. 7.

Referring more particularly to the form of this invention illustrated in Figs. 1 to 3, inclusive, and with particular reference to Fig. 3, it will be seen that the evaporator comprises two unitary sections, each of which is composed of an upper suction header and a spaced lower parallel header 2, the two headers being connected by means of spaced parallel tubes 3 terminating in the headers. The tubes 3 intermediate their terminating ends, in the illustrated embodiment, are bent angularly at substantially right angles at three points 4, 5, and 6 (see Fig. 3) to provide four straight portions lying in different planes, the tubes of each portion all lying in the same plane. The units or sections when turned through 180° and interleaved will define two rectangular refrigerating chambers 7 and 8 (Fig. 2), chamber 7 being directly above chamber 8. Into the chambers thus formed by the interleaving of the two units or sections are inserted two rectangular cylindrical sleeves 9 which serve to retain the two sections in position, i. e., the two sleeves interlock the sections so that they cannot be moved either together or apart. As a further means of securing the sections together in interleaved position, the tubes may be soldered, or otherwise secured at their intersecting points to each other or to the sleeves, or both. If desired, a shelf 10 may be supported across the upper chamber 7 to divide the same into two smaller chambers. For supporting the evaporator, brackets 18 may be secured to the suction headers.

The two suction headers 1 are joined by cross conduits 11, which enter the suction headers above a baffle 12, and communicate with a common suction line 13. A charging tube 14 may also be connected to the suction

line for charging the entire system after which it may be sealed off. The two lower liquid headers are also interconnected through cross pipes 16 and communicate with a common liquid inlet 17.

In the modification illustrated in Fig. 4 the tubes of each section are bent intermediate their ends into three portions only, whereby the tubes when interleaved define only one rectangular refrigerating chamber.

In the modification illustrated in Fig. 5 the tubes of each section are bent into seven straight sections, whereby the units when interleaved will form three rectangular refrigerating chambers, each of which is substantially surrounded by refrigerant tubes.

In the form of this invention illustrated in Figs. 7 and 8, which is substantially equivalent to the form shown in Figs. 1 and 2, it will be seen that the evaporator is composed of two sections each of which involves one header only. Each section comprises an upper header 1 from which bent tubes 3 depend. The tubes instead of being joined to a lower header are returned parallel to themselves and terminate in the same header. That is, both ends of each tube terminate in the upper header. In the illustrated form the tubes are bent to provide the same number of sections as shown in the form illustrated in Figs. 1, 2, and 3, although it is obvious that the tubes may be bent as shown in Figs. 4 and 5, for example. As in the prior forms of this invention, the headers are hooked together by conduits 11 to provide a common suction line 14. The headers are also connected below the internal baffle by a conduit 16^a leading to a common liquid connection 17^a. This form of the invention embodies all of the advantages previously described except that of having the liquid inlet enter the bottom of the evaporator and the advantages resultant therefrom.

From the foregoing description it will be apparent that an evaporator is provided composed of two unitary sections, each of which may be exactly similar in construction, thereby reducing manufacturing cost, and which may be interleaved to provide one or more refrigerating chambers. Each of the chambers will be substantially surrounded by spaced refrigerant tubes which will provide for very efficient transfer of heat.

It is obvious that many forms or shapes of refrigerating chambers may be provided as well as a number of individual chambers, and that other changes in the details of construction may be accomplished without departing from the spirit and scope of the invention as defined in the claims appended hereto.

I claim:

1. In an evaporator, a pair of unitary sections, each section comprising a header and a plurality of spaced refrigerant tubes ex-

tending therefrom and terminating at both ends in said header, the tubes of one section being interleaved with the tubes of the other section to form an enclosure constituting a refrigerating chamber and in such a manner that the tubes of each section bound at least two sides of said chamber.

2. In an evaporator, a pair of unitary sections, each section comprising a header and a plurality of spaced refrigerant tubes extending therefrom and terminating at both ends in said header, the tubes of one section being interleaved with the tubes of the other section to form an enclosure constituting a refrigerating chamber and in such a manner that the tubes of each section bound at least two sides of said chamber, and common connections to the headers for the admission and withdrawal of refrigerant.

3. In an evaporator, a pair of unitary sections, each section comprising a header and a plurality of spaced refrigerant tubes extending therefrom and terminating at both ends in said header, the tubes of one section being interleaved with the tubes of the other section to form an enclosure and in such a manner that the tubes of each section bound at least two sides of said enclosure, a sleeve inserted in said enclosure constituting a refrigerating chamber.

4. In an evaporator, a pair of unitary sections, each section comprising a header and a plurality of spaced tubes extending therefrom and terminating at both ends in said header, the tubes of each section being bent angularly so as to lie in two intersecting planes, the tubes of one section being interleaved with the tubes of the other section to form an enclosure and in such a manner that the tubes of each section bound at least two sides of said enclosure.

5. In an evaporator, a pair of unitary sections, each section comprising a header and a plurality of spaced tubes extending therefrom and terminating at each end in said header, the tubes of each section being bent angularly so as to lie in two intersecting planes, the tubes of one section being interleaved with the tubes of the other section to form a rectangular enclosure and in such a manner that the tubes of each section bound at least two sides of said enclosure.

6. In an evaporator, a pair of unitary sections, each section comprising a pair of spaced headers connected by a plurality of spaced refrigerant tubes terminating in said headers, the tubes of one section being interleaved with the tubes of the other section to form an enclosure surrounded on two sides at least by the tubes of each section, a sleeve inserted in said enclosure and constituting a refrigerating chamber, said sleeve serving to lock said sections against relative movement.

7. In an evaporator, a pair of unitary sections, each section comprising a pair of spaced

headers connected by a plurality of spaced refrigerant tubes terminating in said headers, the tubes of one section being interleaved with the tubes of the other section to form a plurality of enclosures each surrounded on two sides at least by the tubes of each section, sleeves inserted in said enclosures and constituting refrigerating chambers, said sleeves serving to lock said sections against relative movement in at least two directions.

10 In witness of the foregoing I affix my signature.

CARL E. L. LIPMAN.
